UNITED STATES PATENT OFFICE.

WILLIAM B. TURNER, OF NEW YORK, N. Y., ASSIGNOR OF ONE-HALF TO
CORNELIUS BEARD, OF SAME PLACE.

CAR-BRAKE.

SPECIFICATION forming part of Letters Patent No. 294,939, dated March 11, 1884.

Application filed April 26, 1883. (No model.)

To all whom it may concern:

Be it known that I, WILLIAM B. TURNER, a citizen of the United States of America, residing at New York, in the county of New York 5 and State of New York, have invented certain new and useful Improvements in Car-Brakes, of which the following is a specification, reference being had therein to the accompanying drawings.

10 My invention relates to certain improvements in car-brakes of that class in which the motion of the draw-bar is made to operate the brakes, such as that shown in my application filed December 15, 1882; and the invention 15 consists in the construction, arrangement, and combinations of parts, hereinafter described and claimed.

In the accompanying drawings, Figure 1 is 20 a side elevation of part of one end of a car with my improved mechanism attached, part of one of the draft-timbers and the friction-pulley being broken away to show the position of the other parts. Fig. 2 is a diagram of some 25 of the parts shown in Fig. 1 in a different position. Fig. 3 is a plan view of the same, partly broken away. Figs. 4, 5, and 6 are details which will be more fully explained hereinafter.

A A represent the draft-timbers, to which 30 are attached the plates B, forming guides for the plates C, through which the pin of the draw-bar D passes, and between which the spring E is confined. The pin of the draw-bar also passes through the ends of a clevis, F, to which 35 is connected the multiplying-lever G by a link, H. The upper end of this lever G is pivoted between the draft-timbers A A, and as the link H is pivoted to the lever near its center, the motion of its lower end is multiplied by two, 40 and hence I call it the "multiplying-lever." To this lower end is pivoted the bar I, (which I term the "operating-bar,") provided with a double incline or cam, i, near its center, and a tooth or lug, i', and extends rearward with 45 its rear end passing between the jaws of the top of a double bell-crank, J, and resting on a pin, j, that passes laterally through said jaws. The bell-crank J is pivoted at k to a frame, K, which extends forward from the truck-timbers, 50 and to the front and rear ends of said bell-crank

are pivoted rods L L', which extend downward, and each has a slot in its lower end. Underneath the truck-timbers is a box, M, constructed with its front partly open, to admit a spring, N, and the foot of a toggle-joint lever, O, the 55 front end of which is forked and pivoted between the jaws of the bifurcated rear end of the toggle-lever O', which extends forward and encircles the shaft P of the friction-pulley Q, which shaft runs in a slot, k', in the frame K 60 K, which allows of a motion toward the car-axle. Between the forked ends of these toggle-levers O O' the lower ends of the rods L pass, and a joint-bolt passes through all, keeping them connected together. The spring N 65 acts as a yielding fulcrum for the foot of the toggle-lever O to press against, and also to hold the toggle-joint, bell-crank J, and friction-pulley Q in the position shown in Fig. 1, which is caused by the spring pressing against 70 the back of the foot of the lever O, tending to push it out of the box M, while the lower end of the foot of the lever O is engaged against a lug or stop in each lower front corner of the box M, which prevents the escape of the foot 75 from the box, which will tend to throw the forward end of lever O downward, and thus hold the double bell-crank J and friction-pulley Q, as shown.

Embracing the upper edge of the frame K 80 and pivoted thereto is a looped rocking lever, R, which extends upward with its enlarged T-shaped end under the operating-bar I, and in its loop near its center (see Fig. 6) are pivoted two rods, S S', which extend forward and 85 rest on the top of a collar, T, which is rigidly secured to the axle of the car, and is provided with eight ratchet-teeth set in pairs, each member of the pair pointing in opposite directions. The forward ends of rods S S' are provided 90 with teeth, as shown in Fig. 1. The tooth of rod S is arranged to engage with the teeth of the axle-collar T, that point in the direction of the arrow I, and pull the rocking tripping-lever R from the position shown in 95 dotted lines to the position in full lines, Fig. 1, while the tooth of the rod S' is arranged to engage with the teeth of the axle-collar T, that point in the opposite direction, and to push the lever R back to the position shown 100

in dotted lines. This action takes place only on changing the direction of the wheel rotation. Two pins project laterally through frame K, against which lever R rests when in 5 its different positions, as shown in Figs. 1 and 6.

U is the common hand-brake wheel, with its staff extending downward through the car-timber. On the lower end, just beneath the 10 car-timber, is rigidly secured a wheel, V, on one side of which is a circular notch, as shown in full lines in Fig. 5.

W is a lever pivoted at its center to the car-timber, and has connected to its round end r 15 the forward end of rod X, which extends rearward to the top of the lever Y, and is pivoted thereto, as shown in Fig. 1. The lower end of the lever Y is rigidly secured to the cranked rod Z, (see Fig. 4,) which passes across and 20 under the car-timbers A, and is held in eye-bolts attached thereto. The crank part z of rod Z is bent downward and forward, as shown in Figs. 1 and 4, and extends below the operating-bar.

25 Above the crank z is a rod, z', (see Fig. 4,) which may be fixed in the timbers A A or attached to the rod Z, as preferred, which acts as a stop to prevent the operating-rod being jerked too far upward.

30 The action of the hand disengaging device is as follows: Should it be required at any time to render the automatic brake entirely inoperative, as would be the case were pushing and pulling engines used simultaneously, 35 all that is necessary to be done is to turn the hand brake wheel to the right. This turns the notched wheel V, and as the notch therein comes around the point of lever W will be forced to engage therewith by the spring s 40 pushing the point into said notch, and will thus be carried round to the position shown in dotted lines in Fig. 5. As the opposite or round end of lever W will be forced rearward, (in the direction indicated by the arrow 3 in Fig. 45 5,) it pushes the rod X, which forces the top of lever Y rearward, turning rod Z and causing its crank z to rise, thus lifting the tooth of the operating-bar I above the pin j of the double rocking bell-crank J, thus rendering 50 the brake entirely inoperative. The use of the hand-brake wheel to throw the automatic brake out of operation when turned to the right for this purpose in no way interferes with its use as a hand-brake, as it is in this

55 direction that a hand-brake wheel is turned when it is desired to apply the brake by the old plan, and it has the advantage that when the hand-brake is applied the automatic brake will be rendered inoperative, and when the hand-brake is released it will again be rendered operative by the fact of the staff revolving in the opposite direction.

60 The action of the brake is as follows: Suppose the car to be pulled by the engine in the direction of the arrow 1, the draw-bar would be extended, and would (by means of clevis F, rod H, and lever G) pull the operating-bar I

forward, leaving the brake inoperative. If, now, it is desired to stop, the engineer will slow his engine, which will cause a pushing in of 70 the draw-bars, in consequence of the cars running into the engine, from the sudden checking of its momentum, while that of the cars for a time continues. This pushing in of the draw-bars will, through the medium of the 75 draw-bar connections above described, force the operating-bar I rearward, and as its tooth engagess with the pin j of the bell-crank J it will force its top rearward, and as the top moves

80 rearward the front end will rise, and through the medium of the rod L raise the center of the toggle-joint, which increases in length as it rises, and forces the friction-pulley Q forward against the axle-collar T, which will cause the friction-pulley Q to revolve and wind 85 up the chain around its shaft and apply the brakes. The train being now stopped and it is desired to back up, the engine would push against the draw-bar, pushing it rearward, which would, through its connections, push 90

the operating-bar rearward, and as the tooth of the operating-bar engages against the pin j of the bell-crank J, it pushes the top rearward, with the effect of forcing the friction-pulley into contact, as above explained, which, 95

as the wheel revolves backward, would effect an application of the brakes were it not that the tripping device is brought into action. As the axle revolves backward, the tooth of the 100 rod S' will engage with the tooth of the axle-collar, which in its backward motion will force the rod S', and consequently the top of the tripping-lever R, rearward, which in its rearward travel will strike the swell or cam i of the operating-bar I, causing it to rise above 105 the pin j of the bell-crank J, and thus break connection between the draw-bar and friction devices, thus permitting the car to back up without the brake being applied. As the tripping-lever passes rearward of the swell or cam 110 of bar I, said bar falls down again and rests upon the pin j; but as the draw-bar is pushed in when the connection is broken, and the action of the spring N being to always bring the bell-crank J to the position shown in Fig. 1, 115 it is evident that the tooth of the operating-bar I will fall to the rear of pin j of the bell-crank J. If, now, the engine be slowed, the momentum of the cars will operate to pull the draw-bars outward, which will, through 120 their connections, pull the top of the bell-crank J forward, (the tooth of the operating-bar I being in the rear of the pin j and engaged therewith,) and as the top of the bell-crank J is pulled forward the rear end will 125

rise, and through the medium of rod L pull on the center of the toggle-joint, causing it to force the friction-pulley Q into contact with the axle-collar T, which in revolving causes an application of the brake (as before explained) and stops the train. From the above explanation the double action of the draw-bar and brake mechanism will be clearly understood. If the train be now pulled again in 130

the direction of arrow 1, the pulling out of the draw-bar will tend, as before, to force the friction-pulley Q into contact with the collar T for an application of the brake; but as the axle begins to revolve, the hooking-tooth of rod S will engage with tooth of axle-collar T, which will pull the tripping-lever R forward, breaking the connection between the draw-bar and friction-pulley by lifting operating-bar I up, as before explained, and causing the tripping device to assume the position shown in full lines in Fig. 1.

From the above will be seen the automatic principles of the brake mechanism with the engine attached to the draw-bar D.

In order that the automatic principles may be demonstrated with the other end of the car forward, let us assume that the engine is attached to the opposite end of the car, and that other cars are attached to the draw-bar D. If, now, the car be pulled in the direction of arrow 2, the tooth of the axle-collar T will, as the axle revolves, engage with the tooth of the rod S' and push it forward, and consequently the top of the tripping-lever R forward to the position shown in dotted lines in Fig. 1. The tripping-lever R will in its travel lift up the operating-bar I, which will, when the lever R passes from under its cam or swell i, drop down again, and as the draw-bar is being pulled outward by the cars in its rear the tooth of operating-bar I will be in rear of pin j, in which position it is operative to apply the brakes, as before explained, on the pushing in of the draw-bar D with the wheels revolving in this direction. If, now, the engine be slowed and the brakes applied by the draw-bar D being pushed inward by the car in its rear, it is evident from the position of rods S S' that they cannot operate to break the connection between the draw-bar and friction-pulleys. Therefore the axle-collar T would cause the friction-pulley Q to revolve and wind the chain around the shaft P, and thus apply the brakes and stop the train. If, now, it be desired to back the train, the pushing in of the draw-bar would force the friction-pulley into contact; but as the axle revolves backward some one of the four teeth that point in the proper direction will engage with the hooking-tooth of rod S and pull it, and consequently the top of the tripping-lever R, rearward, which, acting on the swell or cam of operating-bar I, will lift up its tooth above the pin j and break the connection between the draw-bar and friction device, and so allow the train to be backed without the brakes being applied. As the operating-bar I falls down and rests again on pin j, its tooth will fall in front of it, from the fact that the draw-bar is pushed inward when the connection is broken; and if the engine is now slowed, the pulling out of the draw-bar becomes operative to apply the brakes in this direction and from this end of the car.

From the above it will be seen and understood that my brake is automatically opera-

tive at any rate of speed, and with either end of the car forward, and in either direction of the draw-bar motion, provided that when the locomotive is hitched to the opposite end of the car to that having the brake mechanism there are other cars behind it to operate upon the draw-bar by their momentum.

As a further evidence of the automatic principles of my brake, let us assume that we have a train of ten cars standing on a side track, five of said cars having been pushed in at one end of said side track, while the other five have been pushed in against them from the opposite end and coupled up in the usual way. It is now desired to attach an engine to said ten cars for the purpose of pulling them out, and it matters not to which end you attach the engine, as the relation of the tripping mechanism to the direction of motion is the same, as will be seen from the fact that all of the cars have been pushed or backed by the engine, but the direction of wheel rotation of five of said cars was the opposite to that of the other five, which will be seen from the fact that they were pushed in at opposite ends of the side track. Now, the cars having all been pushed, it is evident that the pushing in of the draw-bar is non-effective to apply the brakes, but that the pulling out of the draw-bar is effective for such application. If, now, you attach to one end of said train and pull it with the engine, the pulling out of the draw-bar will operate to cause an application of the brakes on all the cars; but the brakes of the first five cars of the train at the end to which you attach the engine will, by their tripping device, be disengaged, there being a change in direction of wheel rotation, while the brakes of the other five cars would not be disengaged, there being no change in the direction of their wheel rotation. This being the case, it would be necessary for the engineer to stop and back up sufficiently to change the direction of motion of all the wheels in his train. This change of direction of wheel rotation would cause the tripping devices of all the cars to assume the same position in relation to direction of motion, and then, when the cars were pulled in the opposite direction again, the brakes would all be automatically adjusted to operate when the motion of the train was resisted by the draw-bar.

That it may be more clearly understood, I would here state that when an engine is attached to a train for the purpose of pushing or pulling it in either direction all that is necessary to be done in order that the brakes be properly adjusted is to move the train one-half of a revolution of the wheels in the opposite direction to which you intend going with the train. Said slight movement will adjust all the brakes to the same direction, and you can then handle the train as you choose, and the brakes will always be effective to stop the train whenever its motion is resisted by the draw-bar.

It is evident that various changes may be

made in the construction without essentially departing from the spirit of my invention. For instance, instead of the double bell-crank lever, made in one piece, as shown, two single bell-crank levers may be used, one of which acts when the draw-bar is being pushed in, and the other when it is pulled out. This I should consider the equivalent of my double bell-crank lever in this connection, as I should to any other form of double-acting lever that acts in opposite directions and performs the same function as mine, except in claims where the bell-crank is specifically named.

Instead of the collar T being on the car-axle, it may be set on a separate shaft, revolved by or with said axle, and instead of having two sets of teeth facing in opposite directions, the teeth may be made broader on their outer surfaces, and each tooth have two acting-sides looking in opposite directions.

I prefer to use the multiplying-lever G; but this may be dispensed with and the clevis connected directly to the operating-bar, if the draw-bar is arranged to have sufficient motion; but, for obvious reasons, the use of the multiplying-lever is preferable.

In view of these various modifications and others which it is obvious may be made by any mechanic conversant with the art, I do not limit myself to the construction shown, except where the claims indicate that such special construction is claimed.

Any novel feature herein shown or described and not claimed I reserve the right 35 to cover by a separate application.

What I claim as new is—

1. In a momentum car-brake operative at all rates of speed, the combination, with the draw-bar and the brakes, of a double-acting 40 lever, a tripping device, and other intermediate mechanism, substantially as described, between the draw-bar and brakes, constructed to operate the brakes when the car is traveling with either end forward and in either direction of the draw-bar's motion, as set forth.

2. In a car-brake operative at all rates of speed, and operated by the contact of friction-pulleys, the combination, with such pulleys and the draw-bar, of double-acting lever, a tripping 50 device, and other intermediate mechanism, substantially as described, between the draw-bar and friction-pulleys, constructed to put such pulleys into operation when the car is running with either end forward and in either direction of draw-bar motion.

3. The combination, in a momentum car-brake, of a draw-bar constructed and arranged to act on the brake through intermediate mechanism in both directions of its movement, and a tripping device constructed to act independently of the brakes or draw-bar, and to operate by and at each change in direction of wheel rotation, substantially as described.

4. The combination, in a momentum car-brake, of a draw-bar constructed and arranged to act on the brake in both directions

of its movement, a double-acting lever, and a tripping device constructed to cause the draw-bar to reverse its action on said double-acting lever, for the purpose set forth.

5. The combination, in a car-brake, of a double-acting draw-bar, a friction apparatus for operating the brake, and double-acting lever and other intermediate connections, substantially as described, between the draw-bar and friction apparatus, constructed to operate the brake with either end of the car forward and at any rate of speed, as set forth.

6. In a momentum car-brake operative at all rates of speed, the combination, with a movable draw-bar and an operating-bar connected therewith, of a friction-pulley and a double-acting lever and other intermediate connections for transmitting the motion of the draw-bar to the friction-pulley, constructed to move said pulley toward its operating means in both directions of the draw-bar's motion, substantially as described.

7. In a momentum car-brake operative at all rates of speed, the combination, with a movable draw-bar, an operating-bar connected therewith, a double-acting lever, a friction-pulley, and mechanism connecting the double-acting lever and pulley, constructed to move said pulley toward its driving-pulley in either direction of draw-bar motion, substantially as described.

8. The combination, with a movable draw-bar, an operating-bar connected therewith, a double-acting lever, a friction-pulley, a toggle-lever for holding the friction-pulley in connection with its driving-pulley, and means for operating said toggle-lever in the same direction in either direction of draw-bar motion, substantially as described.

9. The combination, with the double-acting draw-bar, a double-acting lever, and intermediate connections, substantially as described, between the two, of a toggle-lever for moving the friction-wheel, and links connecting the opposite arms of the double-acting lever with the toggle-levers, as set forth.

10. The combination, with the double-acting draw-bar, a double-acting lever, and intermediate connection, substantially as described, between the two, of a toggle-lever for moving the friction-wheel, a spring-bearing for one end of said toggle-lever, and links connecting the opposite sides of the double-acting lever with the toggle-lever, as set forth.

11. The combination, in a car-brake, of a double-acting draw-bar and a double bell-crank lever, with a reversible connection between said draw-bar and lever, constructed to move said lever in one direction only when in one of its positions, and to move it in the other direction only when its position is reversed, substantially as described.

12. The combination, with a double-acting draw-bar, of a double-acting lever, a loose reversible connection between the draw-bar and lever, acting on said lever in both directions,

and means for holding the latter in its normal position during the reversal, substantially as described.

13. The combination, with a double-acting draw-bar, of a double-acting lever, a loose connection between the draw-bar and lever, acting in both directions on said lever, and mechanism performing the double function of holding said lever in its normal position and moving the friction-pulley, all substantially as described.

14. The combination, in a car-brake operative at all rates of speed, with a moving draw-bar and a double-acting lever loosely connected therewith, of a tripping device constructed to reverse the connection between said draw-bar and lever, whereby said draw-bar, through said loose connection, operates said lever in both directions of the draw-bar's motion, substantially as described.

15. The combination, in a car-brake, of a moving draw-bar connected to a multiplying-lever, a double-acting lever, an operating-bar loosely connecting said multiplying-lever, with the double-acting lever and a tripping device constructed to reverse the connection between the operating-bar and the double-acting lever, substantially as described.

16. The combination, with a moving draw-bar for operating automatic brakes, and a hand-brake device, of a tripping device constructed to break the connection between the draw-bar and the brakes by the action of the hand-brake operating device, substantially as described.

17. The combination, with a moving draw-bar for operating an automatic brake, and a hand-brake device, of a tripping mechanism operated by putting the hand-brake into operation, substantially as described.

18. In a brake mechanism in which the motion of the draw-bar throws the brake into action, the combination, with said draw-bar and its connecting-bar I, of the recessed wheel V, means for operating said wheel, lever W, a tripping device operating on the connecting-bar, and a connection between said lever W and the tripping device, substantially as described.

19. In a brake mechanism, the combination, with the moving draw-bar and an operating-bar connected therewith, of the hand-wheel U, the notched wheel V, the staff connecting said wheels, the lever W, rod X, and tripping device Y Z, substantially as described.

20. In a brake mechanism, the combination, with the moving draw-bar and the operating-bar connected therewith, of a pivoted rocking tripping device acted on by the change of direction of rotation of the car-wheels, and acting directly on the swell of the operating-bar, substantially as described.

21. In a brake mechanism, the combination, with the moving draw-bar and the operating-bar connected therewith, of a rocking lever, two rods pivoted thereto on the same side of its fulcrum, each rod having a tooth facing opposite to the tooth on the other, and a toothed collar provided with oppositely-acting teeth revolving with the car-axle, substantially as described.

22. In a car-brake, the combination, with a double-acting draw-bar, a double-acting lever connected with said draw-bar by a reversible connection, of a tripping device provided with two dogs, each having a tooth set in opposite directions to that on the other, and pivoted above the line of the centers of the car-axles, and a toothed collar constructed to revolve with the car-axle, and to engage alternately with the opposite teeth of the dogs on the change in the direction of wheel rotation, substantially as described.

23. The combination, with the axle of a car, and the double-acting draw-bar D, of the loose clevis F, the multiplying-lever G, connected therewith, the operating-bar I, the double-acting lever J, slotted links L, toggle O O', and friction-pulley N, all constructed and arranged to operate substantially as shown and described.

24. The combination, with the moving draw-bar D, of the loose clevis F, the multiplying-lever G, connected therewith, the operating-bar I, having swell i, the double bell-crank lever J, links L L', toggle O O', pulley Q, connected with the brake, toothed collar T, revolving with the car-axle, rods S S', and the rocking lever R, all constructed and arranged to operate substantially as shown and described.

In testimony whereof I affix my signature, in presence of two witnesses, this 16th day of April, 1883.

WILLIAM B. TURNER.
